UNITED STATES PATENT OFFICE.

CHARLES RIGTER, OF PHILADELPHIA, PENNSYLVANIA, ASSIGNOR TO DORNAN, MAYBIN & CO., OF SAME PLACE.

DESIGN FOR CARPETS.

Specification forming part of Design No. 6,303, dated December 17, 1872.

To all whom it may concern:

Be it known that I, CHARLES RIGTER, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

Claim.

I claim as my invention—
The configuration of the design hereunto annexed when applied to carpeting.

CHAS. RIGTER.
